[57] CLAIM

The ornamental design for a game apparatus, as shown and described.

DESCRIPTION

FIG. 1 is a top, front, right side perspective view of a game apparatus, showing my new design;

FIG. 2 is an enlarged, rear elevational view thereof;

FIG. 3 is an enlarged, front elevational view thereof;

FIG. 4 is an enlarged, left side elevational view thereof, the right side being a mirror image thereof;

FIG. 5 is an enlarged, top plan view thereof; and

FIG. 6 is an enlarged, bottom plan view thereof.

The dice are shown in broken lines for illustrative purposes only.
